W. H. BOSTWICK.

SCAFFOLD.

APPLICATION FILED JAN. 31, 1918.

1,330,162.

Patented Feb. 10, 1920.

UNITED STATES PATENT OFFICE.

WILLIAM H. BOSTWICK, OF NORFOLK, VIRGINIA.

SCAFFOLD.

1,330,162.

Specification of Letters Patent. Patented Feb. 10, 1920.

Application filed January 31, 1918. Serial No. 214,692.

To all whom it may concern:

Be it known that I, WILLIAM H. Bostwick, a citizen of the United States, residing at Norfolk, in the county of Norfolk, 5 State of Virginia, have invented certain new and useful Improvements in Scaffolds; and I do hereby declare the following to be a full, clear, and exact description of the invention, such as will enable others skilled 10 in the art to which it appertains to make and use the same.

This invention relates to scaffolds and particularly to convertible and adjustable scaffolds.

One object of the present invention is to provide a novel and improved device whereby an extension ladder can be quickly and easily converted into a scaffold.

Another object is to provide a novel and improved structure of this character wherein the braces for the device when used as a scaffold are adapted to serve as strengthening means for the device when used as an extension ladder.

Other objects and advantages will be apparent from the following description when taken in connection with the accompanying drawing.

In the drawing:

Figure 1 is a side elevation of the device in the position when used as a scaffold.

Fig. 2 is a top plan view of the same.

Fig. 3 is a front elevation of the device when used as a ladder.

Fig. 4 is a longitudinal sectional view taken on a line through the brace arms 17 and adjacent portions of the sections 11 and 14 of the ladder.

Referring particularly to the accompanying drawing, and especially to Figs. 1, 2, and 3, 10 and 11 represent a pair of ladder sections, each of which is provided with a removable metal rung 12, disposed at a point intermediate the length of the section. One 40 end of each ladder section 10 and 11 is provided with a removable wooden rung 13, the use of which will appear hereinafter. An intermediate section 14 has the third rung from each end removable, as shown at 15,

45 the rung 13 serving as the second rung of each end of the section 14 and the first rung of each section 10 and 11, when the device is used as shown in Fig. 3. The ends of the outermost rungs 13 of the section 14 50 are engaged in the rails of the sections 10 and 11, and serve as the pivots between said

sections. Pivots mounted for swinging movement on the ends of the metal rungs 12, and held thereon by the nuts 16, are the brace links 17. Each of these links has a 60 pair of openings formed in its outer end, as shown at 18, said openings being arranged in longitudinal alinement.

When the device is used as a scaffold, as shown in Figs. 1 and 2, the links have their 65 outer ends disposed at the sides of the ends of the rails of the section 14, the second rung 13, of the end of the section 14, being disposed through the inner openings of the links, while the other rungs 15 are disposed 70 in the other openings of the links, but above and resting on the rails of the section 14. Thus the rungs 13 and 15 serve to hold the sections 10 and 14 against swinging movement. The other ends of the links are 75 formed with additional openings 19 whereby the scaffold can be adjusted to different heights and the sections 10 and 11 at different angles with respect to the section 14 and to the ground or floor.

When the device is used as a ladder the section 10 and the section 11 are swung into the position shown in Fig. 3, that is, in longitudinal alinement with and at opposite ends of the middle section 14. The 85 openings in the inner ends of the side rails of the sections 10 and 11 will then register with the openings in the side rails of the middle section from which the rungs 13 were removed. Into the registered openings 90 of the sections 10, 11, and 14, the removed rungs 13 are placed, thus holding the sections in rigid alinement for use as a ladder, which ladder may be leaned against the 95 wall of a building.

When the device is used as a scaffold, the section 14 lies in a horizontal plane, and a board 20 is placed longitudinally thereon for the workman to stand upon, this board being removed, however, when the device 100 is used as a ladder.

What is claimed is:

1. A convertible ladder and scaffold including a pair of end ladder sections and an intermediate ladder section, the endmost 105 rungs of the intermediate section being pivotally engaged with the end sections to permit movement of the sections into positions at angles to each other and into longitudinal alinement, removable rungs in the end sections adapted to engage through the intermediate section at times to hold the sections 110

in longitudinal alinement and in the intermediate section at times to hold the sections at angles with respect to each other, and links movably carried by the end sections 5 and arranged to receive said removable rungs at times when the sections are in longitudinal alinement and at times when the sections are in positions at angles to each other.

10 2. A convertible ladder and scaffold comprising a pair of end ladder sections and an intermediate ladder section movably connected together and arranged to lie in longitudinal alinement in ladder forming position and at angles with respect to each other in scaffold forming position, links carried by the end sections having openings in 15 the ends of the side rails thereof, the ends

of the side rails of the intermediate section having openings arranged to register with 20 the openings of the end sections at times and with the openings of the links at times, and removable rungs arranged to be engaged through said registered openings in ladder forming position and in scaffold 25 forming position, certain of the removable rungs being arranged to engage through the links and engage with the edge faces of the rails of the intermediate section when in scaffold forming position.

30 In testimony whereof, I affix my signature in the presence of two witnesses.

WILLIAM H. BOSTWICK.
